UNITED STATES PATENT OFFICE.

WILLIAM H. SPEIRS AND ANTON HOLM, OF PATERSON, NEW JERSEY.

ATMOSPHERIC ENGINE.

No. 923,086.

Specification of Letters Patent.

Patented May 25, 1909.

Application filed December 16, 1907. Serial No. 406,751.

To all whom it may concern:

Be it known that we, WILLIAM H. SPEIRS and ANTON HOLM, citizens of the United States, residing at Paterson, in the county of 5 Passaic and State of New Jersey, have invented certain new and useful Improvements in Atmospheric Engines; and we do declare the following to be a full, clear, and exact description of the invention, such as will enable 10 others skilled in the art to which it appertains to make and use the same.

This invention relates to that class of engines in which the piston is driven in one direction by atmospheric pressure, the pressure 15 on the opposite side of the piston being reduced below that of the atmospheric by the condensation of highly rarefied air admitted thereto.

The object of the present invention is to 20 obtain a greater amount of work in an engine with a less consumption of fuel by supplying thereto a working charge of highly rarefied air and in quickly condensing and discharging the same. These objects are obtained by 25 first drawing the flame and products of combustion from a suitable burner, into one end of the cylinder, next in displacing the heated air from the hot end of the cylinder and delivering it into the opposite or cooler end 30 thereof and finally after a movement of the piston has been effected by the condensation of the highly rarefied air and gases in discharging the same from the cylinder.

With these and other objects in view, the 35 invention consists of certain novel features of construction, combination and arrangement of parts, as will be more fully described and particularly pointed out in the appended claim.

40 In the accompanying drawings, Figure 1 is a plan view of an engine constructed in accordance with the invention with parts broken away; and Fig. 2 is a central longitudinal section thereof.

45 Referring more particularly to the drawings, which are for illustrative purposes only and are therefore not drawn to scale, 1 indicates a suitable base upon which is mounted the cylinder 2 of the engine, this cylinder, as 50 shown, being approximately of square form in cross section and comprising a horizontal partition or wall 3, which is spaced a suitable distance below the top wall of the cylinder and extends from the front end to within a 55 suitable distance of the opposite end thereof, leaving a longitudinal hot air passage 5 be-

tween the partition and top wall of the cylinder. The front end of the cylinder is provided with two longitudinally spaced approximately rectangular transverse openings 60 6 and 7, respectively, the former of which is formed in the top wall and partition 3 and 4 and communicates with the extreme front end of the cylinder and the latter of which is formed in the top wall of the cylinder and 65 communicates with the front end of the hot air passage 5. A piston 8 of the proper form is arranged in the cylinder beneath the partition or wall 3 thereof. This piston is provided with the usual rod or stem 9 which extends through the rear wall of the cylinder and is connected with a pair of laterally spaced links 10 fixed to the crank 11 of a crank shaft 12, the latter being journaled in suitable bearings 13 mounted upon the base. 75

The numeral 14 indicates the slide valve which is mounted upon the top wall of the cylinder to cover the openings 6 and 7, this valve being so constructed as to establish communication between these openings and 80 consequently between opposite ends of the cylinder when in one position and to cut-off communication in the next position. This valve is actuated in the proper movement in the work of the engine by a valve stem 15 85 which extends through an upright guide plate 21 arranged at the rear end of the cylinder and is connected with the upright arm 16 of a bell crank suitably mounted at the junction of its arms upon the base, the other arm 90 17 of the bell crank carrying a roller 17' which is disposed in the path of a cam 18 of the proper shape fixed to the crank shaft 12. A coil spring 22 is arranged between the guide plate and a collar 23 formed on the 95 valve rod or stem for moving the latter and the slide valve forwardly. An oil burner or flame generator 19 of any suitable form is mounted on the base in front of the cylinder and a hood 20 arranged in position to conduct the flame and heated air directly to the opening 6. A fly wheel 18' is arranged at one end of the crank shaft, the purpose of which will be evident.

In the operation of this engine thus simply 105 constructed as the piston 8 moves outwardly the slide valve moves in the same direction and discloses the opening 6 through which is drawn the hot flame from the burner 19. As the piston reaches the end of its outward 110 stroke the slide valve closes the opening 6 and shuts off the inflow of hot air into the

cylinder and at the same time establishes communication between the openings 6 and 7, the piston in receding forcing the rarefied air through said openings into the hot air passage 5 and behind the piston into the cooler end of the cylinder, where it continues to condense until the piston has completed its return stroke and has thereby expelled all of the rarefied air from the hot end of the cylinder to the cooler end thereof, under which conditions the internal pressure in the cylinder is far below atmospheric pressure. When the piston reaches the end of its return stroke the valve 14 again opens with the result that the full atmospheric pressure is brought to bear upon the piston to force it outward and cause it to draw in a fresh supply of heated air. As the piston moves outward the charge of condensed air is forced through the exhaust port 24 formed in the top wall of the cylinder.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of

this invention as defined in the appended claim.

Having thus described and ascertained the nature of our invention, what we claim as new and desire to secure by Letters-Patent, is:

An atmospheric engine embracing a cylinder, a piston arranged therein, a flame generator near the cylinder, means for directing the flame from the generator in one end of the cylinder in front of the piston, a slide valve for controlling the admission of the flame into the cylinder, and for establishing or cutting off communication between opposite ends thereof, a longitudinally disposed valve stem for operating the slide valve, a spring around the valve stem to move the valve in one direction, an upright bell crank lever pivotally mounted near the cylinder and connected with the valve stem and means for rocking said lever in one direction against the action of said spring.

In testimony whereof we have hereunto set our hands in presence of two subscribing witnesses.

WILLIAM H. SPEIRS.
ANTON HOLM.
